UNITED STATES PATENT OFFICE.

ALBERT HEWITT DRAKE, OF WATERLOO, IOWA.

TELEPHONE-RECEIVER SUPPORT.

1,142,804.

Specification of Letters Patent. Patented June 15, 1915.

Application filed January 28, 1914. Serial No. 814,945.

To all whom it may concern:

Be it known that I, ALBERT H. DRAKE, a citizen of the United States, and a resident of Waterloo, in the county of Blackhawk 5 and State of Iowa, have invented a new and Improved Telephone-Receiver Support, of which the following is a full, clear, and exact description.

This invention relates to improvements in 10 supporting devices for telephone receivers, and has for an object to provide an improved arm structure for supporting a receiver adjacent the ear when talking.

A further object of the invention is to provide 15 a supporting arm for a receiver which may be shifted from one position to another so that at one time the arm will depress the receiver hook, and at another time the arm will hold the receiver adjacent the ear.

20 In carrying out the object of the invention an arm formed with a clip or holder at one end is provided, said arm being secured in suitable ways to a support, whereby the clamping portion of the arm may be 25 clamped so as to hold the receiver in proper position adjacent the ear when a person is speaking. This supporting arm may be of a number of forms without departing from the spirit of the invention, as for instance 30 the same may be a pivoted arm arranged to depress the telephone receiver hook when in one position and adapted to hold the receiver when in another position. A different form may be provided in which the arm 35 is formed with a knuckle-joint, whereby when the arm is folded the same will depress the telephone receiver hook, and when the arm is extended the telephone receiver hook will be released and the receiver will 40 be arranged adjacent the ear of the speaker.

When an arm is provided for what is known as a desk telephone, a suitable clamping support is also provided which holds the arm in place and permits the parts thereof 45 to properly swing so as to allow the arm to depress the receiver hook when folded, and to hold the receiver adjacent the ear of the speaker when the arm is unfolded.

In the accompanying drawings, Figure 1 50 is a side view of a telephone with an arm embodying the invention applied thereto; Fig. 2 is a view similar to Fig. 1, the same disclosing a slightly modified form of the invention; Fig. 3 is a front view of the upper part of the showing of Fig. 1, the arm

being broken away; Fig. 4 is a side view of a telephone with a modified form of the invention applied thereto; Fig. 5 is a side view of a desk telephone with an embodiment of the invention shown applied thereto; Fig. 6 60 is a top plan view of the showing in Fig. 5; Fig. 7 is a side view of a further modified form of the invention to that shown in Figs. 2 and 4; Fig. 8 is another modified form of the invention; Fig. 9 is a modified 65 form of the invention to that shown in Fig. 5; Fig. 10 is a top plan view of the device shown in Fig. 9, and Fig. 11 is a fragmentary top plan view of the structure shown in Fig. 8.

70 Referring to the accompanying drawings by numerals 1 indicates a telephone of any desired kind provided with the usual mouth-piece 2 and receiver 3. Receiver 3 has associated therewith the usual receiver hook 4, which operates a switch for turning on and off the telephone.

The particular construction of the telephone is no part of the present invention, but several types have been shown in the 80 drawing merely for the purpose of illustration, to show the adaptability of the invention, which is the provision of a supporting member for a telephone receiver. In using an ordinary telephone under ordinary circumstances, it is necessary to hold the receiver by one hand adjacent the ear, and consequently there will only be one hand free for other purposes. By providing a support which will hold the receiver adjacent the ear both hands will be 85 freed from the very tiresome work of holding the receiver while talking and thereby make the speech of the person more natural.

90 In Fig. 1 it will be observed that the arm 95 5 is pivotally mounted at 6 on the telephone 1, and is divided into sections 7 and 8, section 7 being designed to rest against hook 4 when section 8 is moved to an inoperative or folded position. Whenever section 7 100 rests upon hook 4 the same is depressed, and consequently the telephone is shut off or disconnected from the line. Section 8 is connected with section 7 by a pivotal pin 9, and is limited in its pivotal movement by a pin 105 10 acting as a stop which pin alternately engages section 8 in notches 11 and 12. The outer end of the section 8 is provided with a seat 13 for receiving the receiver 3, and clamping arms 14 for clamping receiver 3 110

on to seat 13, whereby the receiver is held on arm 5, and arm 5 in turn operates hook 4.

In operation, when it is desired to use the telephone, arm 4 is adjusted to the position shown in dotted lines in Fig. 1. As section 8 is swung outwardly and section 7 raised, hook 4 will be raised and the telephone switched into the circuit in the usual manner. In order that the arm may remain in the position shown in dotted lines in Fig. 1, section 7 is moved over the stop 15 which is secured to telephone 1, and which is provided with a hook member 16 for preventing the accidental removal of section 7. When the device is in the position shown in dotted lines in Fig. 1 the telephone may be used in the usual manner, that is, anyone may speak into the mouthpiece 2, and may listen to the message through the receiver 3, the receiver 3 being positioned adjacent the ear.

In Fig. 2 a slightly modified form of the invention will be seen in which the arm 17 is solid, whereby the receiver 3 is always held extended. The arm 17 rests upon hook 4 when the telephone is not in use, and is forced over into the stop 15 when the telephone is in use. As the particular construction of arm 17 is the only difference between this structure and that shown in Fig. 1 no additional description will be added.

In Fig. 4 another form of the invention is shown in which the receiver arm 18 is rigidly secured to the telephone 1 by screws or other means so that arm 18 is held against movement but provides a supporting member for receiving the receiver 3, which receiver may be taken off hook 4 and placed in clamps 14 at any time. This form of the invention requires that the receiver be removed from the hook in the usual manner but instead of being held by the hand at a point adjacent the ear the receiver is placed in clamps 14 and is supported by arm 18, thus leaving both hands free for use in any desired manner. After the operator is through speaking it is necessary to remove receiver 3 from clamps 14 and again place the receiver on hook 4. In the form shown in Figs. 1, and 2, it is not necessary to remove the receiver but merely to shift the position of the supporting arms.

In Figs. 5 and 6 another form of the invention is disclosed which, however, is similar to the structure shown in Fig. 1 except that it is adapted for a desk telephone. The desk telephone 1 is provided with a supporting standard 19 of the usual construction around which is clamped a supporting member 20 provided with ears 21 and 22 for receiving the bolts or rivets 23, which bolts or rivets connect the supporting frame 24 to member 20. The supporting frame 24 is provided with an extension through which

the bolts 23 pass and with a body 25 on which are pivotally mounted lugs 26 and 27. Arm 5 is also pivotally mounted at 28 on body 25. Lugs 26 and 27 are pivotally connected together at 29, and are provided with stops 30 and 31, respectively, for limiting the various movements of sections 7 and 8. When it is desired to use the telephone arm 5 is straightened out, as shown in full lines in Fig. 5, but when it is desired to shut off the telephone the receiver 3 is pushed over to the dotted position shown in Fig. 5, and the sections 7 and 8 will assume the dotted position shown in Fig. 5, wherein section 7 rests upon hook 4 and depresses the same, while section 8 rests against stop 31. To use the telephone it is only necessary to move the receiver and sections 7 and 8 from the dotted position shown in Fig. 5, to the full position, which movement is substantially an outward movement of the receiver. By thus arranging the parts a back and forth movement provides for adjusting the receiver adjacent the ear and then adjusting the receiver so that the weight thereof will cause hook 4 to be depressed. It will be observed that when the arm 5 is in the position shown in full lines in Fig. 5 section 8 rests against stop 30, while section 7 presses against stop 31, whereby the sections are held in alinement. It is evident that the clamping member 20 could be arranged at any desired height on standard 19 so as to cause section 7 of arm 5 to properly engage hook 4.

In Fig. 7 will be seen a slightly modified form of the invention to that shown in Fig. 1 wherein the various parts are similar to that shown in Fig. 1 except that the section 8 is provided with a special form of receiver 32 which is arranged with an earpiece 33 extending at right angles to the body 34 of the receiver. The body 34 is rigidly secured to section 8 of arm 5 so that the clamps 14 of the preferred form of the invention are not necessary in this construction.

In Figs. 8 and 11 will be observed a slightly modified form to that shown in Fig. 5 wherein a bracket 40 is formed with bent-over portions 41 and 42, the bent-over portion 42 providing means by which screws or other securing means may be used for holding the bracket in place. The turned-over portion 42 acts as a stop for the pivotally mounted arm 43, which arm has the receiver 3 arranged thereon, and is held in place by suitable bands 44, which bands may be secured to the bent-over portion 45 of arm 43 by any suitable means, as for instance bolts 46. By this construction and arrangement the receiver may be held at a proper place, as shown in dotted lines in Fig. 8, when talking, and when not talking the receiver may be moved to a position out of the way with the arm 43 resting on the

hook 4 so as to maintain the same in a lowered position.

Figs. 9 and 10 will disclose a modified form of the invention to that shown in Fig. 5, which form is of a simpler type. It will be observed that in these figures the clamping member 20' is preferably held in position by suitable rivets or bolts 23', and that one end of member 20' is extended outwardly and forms a bracket 35 which has a lug 36 offset so as to project at right angles to the direction of bracket 35, whereby the arm 38 may rest against the same. Arm 38 is pivoted at 39 to bracket 35, whereby when arm 38 is resting against stop 36, the receiver 3 will be adjacent the ear of the speaker, and when the telephone is not in use the arm 38, together with receiver 3, is moved over to the dotted position shown in Fig. 9, whereupon arm 38 will depress the hook 4.

It will be observed from the various slightly modified forms shown in the drawing and description, the inventor contemplates the use of any kind of a support for a telephone receiver, especially arms which may be moved from one position to another. In forming these arms which may be moved from one position to the other two different types are provided, one which swings from its pivotal support, and the other of which has an intermediate joint or elbow structure, whereby the parts of the arm may be folded together or to a certain predetermined position.

What I claim is—

1. In a telephone receiver support, the combination with a telephone, of a bracket secured to said telephone, a pair of links 40 pivotally connected with said bracket, means for connecting the outer ends of said links together, a stop arranged on each of said links, an arm pivotally mounted on said bracket adjacent the pivotal mounting of one of said links on said bracket, said arm extending between said stops, means arranged on the outer end of said arm for supporting a telephone receiver, said arm being formed in sections, means for pivotally connecting said sections at a point between said stops whereby when the outer section of said arm rests on one of said stops, said arm will be out of contact with the hook of said telephone, and when said outer section rests against the other of said stops the inner section of said arm will rest against said telephone hook and depress the same, substantially all of the weight of said outer arm and said telephone receiver bearing on said inner arm when said outer arm

is resting against said second mentioned stop.

2. In a telephone receiver support, the combination with a telephone, of a bracket secured to said telephone, a pair of links 65 connected with said bracket, formed with stops, and a pivotally mounted arm arranged on said bracket and extending between said stops, said arm being provided with means for receiving a telephone receiver, and with a pivotal joint intermediate the length, whereby part of the arm may be folded over the remaining part, said bracket and said arm being so arranged as to cause part of said arm to depress the telephone hook of said telephone when the parts of the arm are folded.

3. In a telephone receiver support, the combination with a telephone, of a bracket secured to said telephone, an arm pivotally mounted on said bracket and arranged to extend above and past the hook of said telephone, said arm being formed into an inner and outer section, means for pivotally connecting said sections together, a stop arranged on each side of said pivotal connection and in the same horizontal plane, said stops acting as a rest for said outer section, and means arranged on the outer section for supporting a receiver, the arrangement 80 of said stops and pivotal connection being such that the weight on the outer section will hold the inner section against the lower side of one of said stops, while the outer section rests on the top of the other stop 85 when the telephone is in use, and said outer section will rest against said first mentioned stop when said telephone is not in use and said inner section will rest on said hook.

4. In a telephone receiver support, the combination with a telephone, of a bracket secured to said telephone, a pair of stops associated with said bracket, an arm pivotally mounted on said bracket, said arm extending over the hook of said telephone, said arm being formed with a joint, said joint being arranged between said stops so that when the arm is extended the inner end of the outer section rests on one of said stops and the outer end of the inner section rests 105 against the other of said stops, and means for holding a receiver on the end of said arm.

In testimony whereof I have signed my name to this specification in the presence of 115 two subscribing witnesses.

ALBERT HEWITT DRAKE.
